CLAIM

The ornamental design for a blender base, as shown and described.

DESCRIPTION

FIG. 1 is a perspective view of an embodiment of a blender base showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings illustrate part of the container form no part of the claimed design.

1 Claim, 7 Drawing Sheets

Related U.S. Application Data

continuation of application No. 29/519,682, filed on Mar. 6, 2015, now Pat. No. Des. 793,153.
